UNITED STATES PATENT OFFICE.

HOMO FABER, OF CHICAGO, ILLINOIS, ASSIGNOR OF ONE-HALF TO JOHN J. BREDSHALL, OF SAME PLACE.

DESIGN FOR A MUSICAL-INSTRUMENT BODY.

SPECIFICATION forming part of Design No. 32,849, dated June 19, 1900.

Application filed July 10, 1899. Serial No. 723,427. Term of patent 14 years.

To all whom it may concern:

Be it known that I, HOMO FABER, a citizen of the United States, residing at Chicago, in the county of Cook and State of Illinois, have 5 invented a new and original Design for a Musical-Instrument Body, of which the following is a specification.

My design is illustrated in the accompanying drawings, in which—

- 10 Figure 1 represents a perspective view of a body for a musical instrument embodying my invention. Fig. 2 represents a plan view of the body thereof.
- 15 The leading feature of my design consists of a flat body which when viewed on its edge from any direction presents parallel lines for its opposite faces or, in other words, a rectangular outline, but when viewed from either of its flat faces or sides has the general
- 20 shape of an irregular pentagon, two sides of which are straight and at right angles to each other and the other three sides of which are curved and merge from one side to the other upon curved lines, two of such sides being
- 25 substantially at right angles to the straight sides and the intermediate side being substantially oblique to the straight sides. One face of the flat body has a circular perforation therein slightly to one side of the center
- 30 of the body and about equidistant from one of the straight sides and one of the curved ends thereof.

Referring now to the accompanying drawings, A indicates the flat body, having edges 35 at right angles to its opposite faces, which body when viewed on its face is of a generally-irregular pentagonal form, having two straight sides B and C at right angles to each other and three curved sides D, E, and F, 40 the curved sides merging into each other and

into the straight sides on the arcs of a circle, the sides D and F being substantially parallel with the straight sides B and C, while the side E is substantially oblique to the straight sides B and C. Along the straight sides C 45 is an oblong box G, disposed about the mid-length of said side and open toward the center of the instrument. On the opposite curved sides D and E is located a low bridge H, which is angular at one end, so that it extends substantially parallel with the sides D and E. The body A has a circular perforation I therein to one side of the center and about midway between the ends B and F, and near the edge of the body, opposite the box G, 50 is another bridge H, which is angularly disposed, one part thereof extending substantially parallel with the side E and the other part thereof extending substantially parallel with the side D. On the straight side B is 55 another oblong box K, open on the side toward the center of the body, and a straight bridge L is near the opposite edge F of the body and substantially parallel with said edge. The generally-irregular pentagonal 60 shape of the body, with the oblong body on the straight edges of the body and the bridges along the curved edges of the body, gives to the instrument-body a characteristic and distinguishing appearance. 65

Having thus fully described my invention, what I claim, and desire to secure by Design Letters Patent, is—

The design for a musical-instrument body, substantially as herein shown and described. 75

HOMO FABER.
